United States Patent Office.

HENDERSON ROSS AND DAVID F. AGNEW, OF PITTSBURG, PENNSYLVANIA.

Letters Patent No. 92,478, dated July 13, 1869; antedated June 30, 1869.

IMPROVEMENT IN FURNACES FOR MANUFACTURING IRON AND STEEL.

The Schedule referred to in these Letters Patent and making part of the same.

To all whom it may concern:

Be it known that we, HENDERSON ROSS and DAVID F. AGNEW, of Pittsburg, in the county of Allegheny, and State of Pennsylvania, have invented a new and useful Improvement in Furnaces Used in the Manufacture of Iron and Steel, the same being an additional improvement of the furnace for which Letters Patent of the United States were granted to said HENDERSON ROSS, January 28, 1868; and we do hereby declare that the following is a full, clear, and exact description thereof, reference being had to the accompanying drawings, and to the letters of reference marked thereon.

The nature of our invention consists in extending the water-chamber of the neck of the furnace above the water-level in said furnace-neck, to allow room for the steam and expansion of the water, caused by the heat of the furnace.

To enable others skilled in the art to make and use our invention, we will proceed to describe its construction and operation.

In the accompanying drawings, which form part of our specification—

Figure 1 is a perspective view of our improvement in neck of a furnace used in the manufacture of iron and steel.

Figure 2 is a vertical and longitudinal section of the same when cut through at line *y*, fig. 1.

Figure 3 is a vertical and transverse section of the same when cut through at line *e*, fig. 1.

We construct the neck of the furnace in any of the known forms.

The walls of the neck are made of sheet-metal of any suitable thickness, and the several parts constituting the neck are riveted together, so as to make the water-chamber "water-tight."

The other parts of the furnace, fire-chamber, bosh, &c., are constructed in the usual manner, and of the ordinary material.

In the accompanying drawings—

A is the neck of the furnace.

B is the lower part of the stack.

C is the water-chamber, which extends over the top, around the stack, and down the sides of the neck.

The water-level in the chamber *C* is indicated by the line *f*. The space above the line *f* is made for the purpose of allowing room for the expansion of the water, and for steam caused by the heat of the furnace. This space above the line *f* will prevent any overflowing of the water from chamber *C*.

The water-chamber *C* is provided with an opening, *x*, which may be made large enough to admit the person who enters the chamber, for cleaning or repairing it.

The chamber *C* should be provided with a suitable supply-pipe, for conveying water into the chamber, and a waste-pipe, for carrying off the waste-water from it.

The neck may be provided with a door, at *h*, for the purpose of cleaning out the neck.

Having thus described the nature, construction, and operation of our improvement,

What we claim as of our invention, is—

The extension of the water-chamber above the water-level, said water-chamber being constructed, arranged, and operating substantially in the manner and for the purpose herein described and set forth:

HENDERSON ROSS.

D. F. AGNEW.
